UNITED STATES PATENT OFFICE.

JOHN A. THOMPSON, OF DES MOINES, IOWA.

LIGHT-DIMMER.

1,153,464.

Specification of Letters Patent.

Patented Sept. 14, 1915.

Application filed January 26, 1914. Serial No. 814,367.

To all whom it may concern:

Be it known that I, JOHN A. THOMPSON, a citizen of the United States, residing in Des Moines, county of Polk, and State of Iowa, have invented a new and useful Improvement in Light-Dimmers, of which the following is a specification.

The object of my invention is to provide means, simple, strong, durable and inexpensive, for dimming automobile lights and the like.

A further object is to provide such a means to be operated by the driver without the necessity of leaving his seat.

15 A further object is to produce the desired effect without altering the size of the flame thus making it unnecessary to lose the time incident to the proper adjustment of the gas flow in gas lamps.

20 My invention consists of certain details of construction hereinafter set forth, pointed out in my claims and illustrated in the accompanying drawings, in which—

Figure I shows a front elevation view of 25 a gas lamp fitted out with my device and Fig. II shows a sectional view taken on the line 2—2 of Fig. I.

Referring to the accompanying drawings the reference numeral 10 is used to indicate 30 a gas lamp, the numeral 11 the gas tip, and the numeral 12 the reflector. Secured to the shaft of the tip is an arm 13 to which is pivotally mounted a swinging lever 14 on one end of which is secured a disk 15. This disk 35 may be of the convex conformation shown, or of any other desired shape, and is designed to be of larger size than the flame. To the other end of the lever 14 is secured a small wire cable 16 or the like, which extends downwardly and rearwardly through 40 the lamp to a convenient connection near the driver's seat. I show no particular connection for the said wire 16, my intention being to utilize any connection which will 45 secure the wire after it has been pulled rearwardly and will also provide means for retaining it in its normal position the wire being projected forwardly to such extent as to permit the disk 15 to assume its downward position, as shown by the dotted lines 50 in the drawing. By construction, the arm 13 and lever 14 are so arranged that a downward movement of the lever 14 (caused by pulling the wire 16) will elevate the rear portion thereof throwing the disk 15 into

position immediately behind the flame and completely cutting off the rays from contact with the reflector 12. It is obvious that thereafter the light will not have the great intenseness caused by the reflector. The 60 wire is secured in proper position as long as this dimming effect is desired. When the bright penetrating light is again desired the wire is released and the lever 14 (weighted by the disk and its length from 65 the fulcrum to the rear extremity) assumes its normal position shown in the dotted lines.

Any other means may be employed, with an equal degree of success, for causing the 70 disk to move downward to its normal position, and I wish it understood that I do not limit myself to the means shown, my object being accomplished when I provide for a downward position for the disk which will 75 remove it as an obstruction between the flame and the reflector and an upward position for the reflector which will cause it to constitute such obstruction. My device may also be applied to electric lamps, and others, 80 with equal success and it is my purpose to so use it.

Having thus described my invention what I claim and desire to secure by Letters Patent of the United States is:

1. A light dimmer, including an obstruction, a fixed member outstanding at an angle to the axis of a burner tube, a member fulcrumed upon said outstanding fixed member, with its longer arm bearing said obstruction, and means attached to the shorter arm of said fulcrumed member for actuating the same, which obstruction is arranged to be brought intermediate the light and its reflector by exerting a pulling action upon 95 said actuating means.

2. A light dimmer, including a fixed arm outstanding at an angle to the axis of a burner tube, a member fulcrumed upon said outstanding arm, said fulcrumed member having a disk at the end of its longer arm, and a flexible member attached to the shorter arm of said fulcrumed member for moving said disk to a point intermediate the light and its reflector.

J. A. THOMPSON.
